WEAR INDICATING DEVICE FOR DRILL BITS

John C. Stokes, Houston, Tex., assignor to Reed Roller Bit Company, Houston, Tex., a corporation of Texas

Application March 4, 1949, Serial No. 79,547

7 Claims. (Cl. 255—61)

1

This invention relates to new and useful improvements in wear indicating device for drill bits.

In well drilling, maximum efficiency is obtained when the drill bit, which is attached to the lower end of the drill pipe, is used until it is substantially dull and is no longer capable of performing the drilling operation. Because the bit is carried by the lower end of the drill pipe, it is apparent that the removal of said bit involves removal of the entire drill pipe string which is an expensive operation, requiring considerable time and labor. Thus, if the drill bit is removed before it has been dulled, an unnecessary removal of the drill pipe string has occurred. If, on the other hand, the drill bit is not removed when dull, drilling efficiency is impaired.

It has heretofore been the practice to rely solely upon the driller and his particular knowledge based on experience with respect to the time when the drill bit had dulled and should be removed and obviously, the human element of error has always been present with the result that in many instances, the bit is "pulled" or removed from the well either prematurely or too long after the bit has lost its drilling efficiency. Furthermore, the driller depends solely on "feel" in making his decision as to removal of the drill bit any many variable conditions which may occur in the well bore become factors which cause error, regardless of the experience of the driller. Therefore, because the determination of the dullness of the bit has been based on the personal or individual opinion of the driller many errors of judgment constantly occur and result in erroneous withdrawal of the bit, thereby increasing the cost and reducing the efficiency of the over all drilling operation.

It is one object of this invention to provide an improved indicating device which will automatically signal to the surface when the drill bit is worn to a predetermined point, whereby accurate information as to the condition of the drill bit is made known to the driller or operator.

An important object of the invention is to provide a wear indicating device for drill bits wherein the pressure of the drilling fluid is utilized as a signalling medium and also wherein a sudden variation in said pressure is indicative of the fact that the bit has been worn to a predetermined point.

A further object is to provide a device, of the character described, having means for causing a relatively small pressure variation in the circu-

lating fluid when the drill bit wears to a predetermined point, together with means for utilizing the small pressure variation to actuate apparatus which causes a relatively large pressure variation in the circulating fluid, whereby the pressure variation is clearly noticeable as a signal at the surface.

Still another object is to provide an improved indicating device which may be readily applied to a drill bit of ordinary construction and which includes a normally closed wear tube located exteriorly of the bit and communicating with the drilling fluid circulating through the bit body; said tube having such length and being so disposed that the normal drilling operation will wear said tube to open the same when the bit has worn to a predetermined point, whereby a pressure drop in the circulating fluid occurs as soon as said tube is opened, which pressure drop may be utilized to signal to the surface.

Another object is to provide a device which lends itself to ready adjustment so that a signal may be transmitted to the surface when the bit is completely worn or when the bit has worn to any predetermined point at which it may be desirable to remove said bit.

A particular object of the invention is to provide an improved device, of the character described, having a relatively large, normally closed discharge port which is mounted in the drill bit body and which is subjected to the pressure of the circulating drilling fluid, together with means for opening said port when the drill bit has worn to a predetermined point, whereby a sudden relatively large drop in the pressure of the circulating drilling fluid occurs to immediately signal the condition of the bit to the surface in a noticeable manner.

Other and further objects of this invention will appear from the following description.

In the accompanying drawings which form a part of the instant specification and which are to be read in conjunction therewith and wherein like reference numerals are used to indicate like parts in the various views:

Figure 1 is an elevation of a drill bit having the improved indicating device constructed in accordance with the invention mounted thereon.

Figure 2 is a bottom view of the drill bit.

Figure 3 is a transverse sectional view of the indicating device taken on the line 3—3 of Figure 1 and showing the device before actuation.

Figure 4 is a view similar to Figure 3 illustrating the position of the parts when the wear tube

has been opened due to the wearing of the bit blades to a predetermined point, and

Figure 5 is a view similar to views 3 and 4, illustrating the signalling port completely open.

In the drawings, the numeral 10 designates a bit body which has the usual threaded box 11 at its upper end whereby the bit may be connected to the lower end of the drill pipe or stem. The usual fluid cavity 12 is formed in the bit body and cutting blades 13 are welded or otherwise secured to the lower portion of said body. Drilling fluid circulating passages 14 extend from the cavity 12 and discharge from the lower portion of the body adjacent the blades 13 (Figure 2). As illustrated, the blades 13 are disposed transversely of the bit body and have their lower cutting edges 13a located in a plane below the lower end of the body. When the cutting blades have been worn through the drilling operation to approximately the line indicated at A in Figure 1, it is desirable that the bit be replaced, for at this point said bit is completely dulled.

For indicating that the bit blades 13 are worn down to the point indicated by the line A, the improved indicating device B is arranged to be mounted on the bit body 10. This device includes an annular sleeve or cylinder 15 which is threaded into an opening 16 in the wall 10a of the bit body. The outer portion of the sleeve which extends outwardly from the body may be of angular or hexagonal shape as indicated at 17 to facilitate rotation of the sleeve or cylinder by means of a suitable wrench.

The sleeve or cylinder 15 is formed with an axial bore 18 which extends entirely therethrough and the inner end of the bore is open to the cavity 12 within the bit body whereby the drilling fluid which is circulated through the cavity may flow into the inner end of the sleeve or cylinder. The outer end of the bore 18 of the sleeve is closed by a metallic disc 19 which is welded or brazed in position against an internal shoulder 20 formed within the bore. The disc has a relatively thin wall and has sufficient strength to withstand the pressure of the drilling fluid which is normally circulated through the cavity 12 during the drilling operation. A wear tube 21 has its inner end mounted and suitably fastened, as by welding, within a radial opening 22 formed in the wall of the sleeve or cylinder 15 and the outer end of the tube is closed as indicated at 23. Thus, the drilling fluid which is circulated through the cavity 12 may flow into the sleeve 15 and from said sleeve into the tube 21. The tube has its lower closed end 23 disposed in a plane which is in substantial alignment with the line A and said tube extends contiguous to the trailing face of one of the blades 13, being spaced inwardly from the outer vertical edge 13b of the bit blade. Thus, during normal drilling operations the wear tube 21 is unaffected and it is only when the bit blades 13 are worn down to the point indicated by the line A that the end of the tube 23 is subjected to any abrasive action. Upon wearing down of the blades to the line A a subsequent rotation of the bit results in a wearing away of the closed end 23 of the tube 21.

To effect a considerable variation in the pressure of the circulating drilling fluid when the wear tube 21 is open and thereby provide a signal at the surface, a piston member 24 is mounted within the bore 18 of the sleeve or cylinder 15. This piston member is illustrated as a flanged cup having an axially disposed punch 25 formed

integral therewith. Restricted equalizing orifices 26 are provided in the base of the piston member, whereby when the end 23 of the wear tube 21 is closed, pressures across the piston are substantially equalized and said piston will more or less be hydrostatically balanced. At such time, there will be no appreciable force tending to move the piston in either direction. Displacement of the piston inwardly into the cavity of the drill bit is prevented by an internal overhanging shoulder 18a which is provided at the inner end of the bore of the sleeve or cylinder. The punch 25 has a lower pointed end which is sufficiently sharp to puncture the closure disc 19 when the piston 24 is moved under a predetermined force against said disc.

In the operation of the device, the assembly is mounted on the body 10 of the drill bit with the sleeve or cylinder 15 being threaded into the opening 16 in the bit body. The wear tube 21 has its lower end 23 closed and said tube has a pre-determined length which disposes this lower closed end in a plane opposite the line to which the cutter blades 13 of the bit will be worn before a signal is given. With the wear tube having its end closed the drilling fluid within the cavity 12 may enter the inner end of the cylinder and may pass through the restricted orifices 26 to enter the bore 18 between the piston 24 and the closure disc 19 and to also enter the interior of the wear tube 21. Normal drilling is carried out with the drilling fluid being circulated downwardly through the drill pipe (not shown), and cavity 12, and through the discharge ports 14 of the bit. As has been stated, the closure disc 19 is of sufficient strength to stand the normal pressure of the circulating fluid during the drilling operation and since the wear tube is disposed contiguous to the rear face of the bit blades and is actually within the confines of the exterior surface of the bit body as shown in Figure 2, said tube will not be subjected to any wear during such normal drilling. As the bit blades 13 become worn through drilling until said blades wear to the plane indicated by the line A, which is in the same plane as the lower end 23 of the wear tube, the abrasive action of the formation against the closed end 23 of the wear tube 21 will result in a wearing away of said end 23 whereby the wear tube is opened. As soon as the end 23 of the tube is worn to open said tube, the fluid within the tube and also within the bore of the cylinder 15 between the closure disc 19 and piston 24 is released and may flow outwardly into the well bore. Because of the restricted orifices 26 there is an immediate pressure differential set up across the piston 24 and the considerably higher pressure of the drilling fluid within the cavity 12 of the drill bit will move the piston outwardly with sufficient force to cause the punch 25 to puncture the closure disc 19, as illustrated in Figure 4. As soon as the disc 19 is punctured the circulating drilling fluid which is under a pressure is forced outwardly through the orifices 26 in the piston 24 and then outwardly through the space around the opening 27 in the disc 19 which opening has been formed by the punch. The abrasive action of this fluid under pressure passing through the relatively restricted openings 26 in the piston and the opening 27 in the disc will result in a rapid wearing away of the base of the piston and of the closure disc. Thus, in a relatively short period after the closure disc 19 is punctured, said disc and the piston 24 are completely displaced to entirely open the en-

larged bore 18 of the cylinder or sleeve. Complete opening of this relatively large bore results in a considerable pressure drop in the pressure of the fluid being circulated downwardly through the drill pipe (not shown), and the cavity 12 and this pressure drop provides an indication at the surface which advises the driller that the bit blades have worn down to a predetermined point and that replacement of the bit is advisable.

It is pointed out that the arrangement provides the relatively small tube 21 which is desirable because the smaller tube may be mounted in close relationship to the bit body and danger of accidental severing or breaking off thereof during normal drilling is substantially eliminated. However, the smaller tube has the disadvantage of not providing a noticeable signal because its small, cross-sectional area provides only a relatively small pressure drop which might go unnoticed by the driller. The use of a larger tube would provide a larger pressure drop upon opening of the end thereof, but as stated, a larger tube would be more liable to accidental breakage during normal drilling which would result in an erroneous indication. The present device contemplates the use of a small tube which when opened functions to actuate the piston 24 and thereby open a larger bore so that an ample pressure drop for signalling purposes will occur in the circulating fluid.

The invention is shown as applied to the usual blade type drilling bit but it is apparent that the device may be employed with any of the ordinary bits now in general use. It is, of course, desirable that the lower end of the wear tube 23 be disposed in the plane to which the cutting members are worn when the bit is dull, but there may be instances where it is desired to remove the bit before it is completely dull; in such case, it is only necessary to vary the length of the tube 21 so as to locate its closed end 23 in the desired plane.

From the foregoing it will be seen that this invention is one well adapted to attain all of the ends and objects hereinabove set forth, together with other advantages which are obvious and which are inherent to the structure.

It will be understood that certain features and sub-combinations are of utility and may be employed without reference to other features and sub-combinations. This is contemplated by and is within the scope of the claims.

As many possible embodiments may be made of the invention without departing from the scope thereof it is to be understood that all matter herein set forth or shown in the accompanying drawings is to be interpreted as illustrative and not in a limiting sense.

Having described the invention, I claim:

1. The combination with a drill bit having cutting elements and having a drilling fluid circulating therethrough, of a wear indicating device including, an annular member mounted in the body of the bit and having its inner end communicating with the interior of the bit body whereby the drilling fluid may enter said member, a closure normally closing said member, and a fracturing means within the member and operable when the cutting elements have worn to a predetermined point to open said closure and allow flow through the member to cause a variation in the pressure of the circulating fluid.

2. In combination, a drill bit having cutting elements and also having an opening in the wall of its body, means for circulating a pressure drill-

ing fluid through said bit, a wear indicating assembly mounted in the opening in the drill bit body and including, a cylinder, a closure for closing the outer end of said cylinder, piston means

5 within the cylinder adapted to move into engagement therewith to fracture said closure, means for maintaining said piston means normally in a position adjacent said closure by an equalization of pressures thereacross, and means actuated when the cutting elements have been worn a predetermined amount by a drilling operation for unbalancing pressures across said fracturing means, whereby said means is moved into engagement with the closure to fracture the same and thereby allow flow through the opening in the bit body to vary the pressure of the drilling fluid circulating through the bit.

3. A wear indicating device adapted to be mounted on a drill bit including, an annular supporting member mounted in the body of the bit and having its bore communicating with the pressure drilling fluid within the bit body, a closure for the outer end of the member, a wear tube extending from the member and having one end 20 communicating with the bore thereof and its opposite end normally closed, the closed end of said wear tube being adapted to be opened when the drill bit cutting elements have worn a predetermined amount, and piston means within the annular supporting member movable into engagement with the closure when the end of the wear tube is opened to open said closure and allow flow through said member and thereby produce a drop in the pressure of the drilling fluid within 25 the bit body.

4. The combination with a drill bit having cutters and having a pressure drilling fluid circulating therethrough of a wear indicating device including, a wear element mounted exteriorly of the body and having its inner end communicating with the pressure fluid within the bit, the outer end of said element being closed and being disposed in a predetermined plane with respect to the cutters of the bit, whereby after 40 said cutters have worn a predetermined amount the closed end of the element is also worn and is thereby automatically opened, the bit body having an enlarged passage therein, a closure for said passage, and piston means within the passage and engageable with the closure when the wear element is opened to remove the closure and allow flow of the pressure drilling fluid through said passage, whereby a pressure variation is caused to occur in the drilling fluid.

5. In combination, a drill pipe, a drill having drilling cutters mounted on the lower portion of said pipe, means for circulating a pressure drilling fluid through said pipe and through a passage in said bit, means normally closing said passage in the bit, means for causing a relatively small pressure drop in the pressure of the circulating drilling fluid when the cutters have worn a predetermined amount, and a movable piston within the bit passage actuated by the 55 relatively small pressure drop to remove the closure and open the passage and thereby effect a relatively large drop in the pressure of the circulating drilling fluid, whereby a signal of the wearing of the cutters to said predetermined point is given at the surface.

6. In combination, a drill pipe, a drill bit attached to the lower end of the pipe and having cutters thereon, means for circulating a pressure drilling fluid downwardly through said pipe and bit, the body of the bit having a cylinder

therein, a closure for one end of said cylinder, a piston member adjacent said opening and having means for puncturing said closure, said member normally having opposite sides exposed to the pressure of the circulating fluid and disposed in spaced relation to the closure, and a wear tube having a closed end communicating with the area between the piston member and closure, said wear tube being opened to unbalance pressures across the piston when the cutters of the bit have worn a predetermined amount, whereby the pressure of the drilling fluid may act upon the piston to move the same into engagement with the closure to puncture the same and thereby allow a flow of drilling fluid through the opening to reduce the pressure of said fluid within the bit and pipe and provide a signal at the surface.

7. In combination, a drill pipe, a drill bit attached to the lower end of the pipe and having cutters thereon and also having a passage extending outwardly through the wall thereof, means for circulating a pressure drilling fluid downwardly through said pipe and bit, a cylinder within the passage, a closure closing the outer end of said cylinder, a piston within the cylinder and having means on that side adjacent the closure for puncturing said closure, said piston also

having openings therethrough whereby pressures thereacross may be equalized, and a wear tube extending from the cylinder exteriorly of the bit and communicating with the area between the piston and the closure, the outer end of said wear tube being closed and being adapted to be opened by wear when the cutters of the bit have worn a predetermined amount, whereby the area between the piston and closure is opened to unbalance pressures across the piston and thereby move said piston into engagement with the closure to open the same.
